UNITED STATES PATENT OFFICE.

MAURICE ALLAND, OF ATLANTIC CITY, NEW JERSEY.

WRITING INSTRUMENT.

Application filed December 6, 1923. Serial No. 678,855.

To all whom it may concern:

Be it known that I, MAURICE ALLAND, a citizen of the United States, residing at Atlantic City, in the county of Atlantic and 5 State of New Jersey, have invented certain new and useful Improvements in Writing Instruments, of which the following is a specification.

The object of this invention is to provide 10 an improved writing instrument, comprising the combination of a magazine pencil and a pen of the co-called "fountain" type.

Another object is to provide such an instrument with a pencil-mark eraser carried 15 by the pen portion of the instrument and with an ink-mark eraser carried by the pencil portion of the instrument.

Still another object is to provide a pencil 20 portion of the instrument, means, connected with the piece of lead being used, which is adapted to co-operate with other means within the pencil casing, whereby the extent to which the lead projects from said casing is automatically governed in accordance 25 with predetermined details hereinafter set forth.

A further object is to provide such a pencil with an elongated cylindrical eraser, means for operatively supporting said 30 eraser, and means for actuating said supporting means, whereby when the exposed portion of the eraser is worn away the supporting means permits the cylindriform member to be withdrawn further, and then 35 clamped so as to prevent its accidental retreat into the pencil casing.

In those types of fountain pens which are filled by means of a dropper, or the like, after removal of the pen-point supporting 40 head, it may be possible to completely fill the reservoir, though this type is not only uncleanly but practically obsolete. However, difficulty has been encountered in filling the reservoir to the same degree, when employing 45 any of the various collapsible tube reservoirs in constructions less likely to spill ink and soil the fingers when filling, as the action in this case depends upon the expulsion of air from the tube, and commercially feasible 50 mechanisms for collapsing the tube apparently fail to expel all of the air therefrom, and resultingly draw in only a portion of a full ink content.

A still further object is to provide a cylindrical reservoir having non-flexible and

preferably transparent side walls, a piston adapted to reciprocate therein throughout the entire longitudinal extent of said cylinder, and a rod extending slidably through that end of said cylinder opposite to the pen-supporting head, said rod being engageable with said piston by means of an angular movement to reciprocate said piston to expel the air from the cylinder and then by a counter reciprocation to draw a full content of ink into said cylinder, after which another angular movement of the rod disengages the same from the piston, to permit the rod to be slid into the reservoir, to prevent interference with the convenient use of the pen.

And a still further object of the invention lies in the construction of the piston, that is providing a radially yielding member, secured between oppositely positioned heads, which are preferably secured together, and means to prevent movement of said member with respect to said heads; also improved means for connecting to and disconnecting said actuating rod from operative relation with respect to said piston; and also providing an abrasive ink eraser upon a cap member which normally surrounds and incloses the pen when not in use.

Additional objects and advantages of the present invention are fully brought out in the following description, when read in conjunction with the accompanying drawings, in which Fig. 1 is a longitudinal view of one embodiment of the invention, showing the pen portion in section; Fig. 2 is a similar view showing the pencil portion in section; Fig. 3 is an enlarged fragmentary view of a portion of the pen section of the device; Fig. 4 is a similar view of another portion of the said pen section; Fig. 5 is a similar view of a portion of the pencil section of the device; Fig. 6 is a section on the line 6-6 of Fig. 2; Fig. 7 is a section on the line 7-7 of Fig. 2; Fig. 8 is a section on the line 8-8 of Fig. 1; and Fig. 9 is a section on the line 9-9 of Fig. 1.

Referring to the drawing, the pen portion of the instrument will first be considered. This portion comprises a hollow cylindrical member 1, both internally and externally threaded at one end 2, the inner threads of which are adapted to receive in normally water-tight engagement, yet removable therefrom, the channelled head 3 which op-

eratively supports the pen-point 4. The opposite end of said member is closed by a transversely extending wall 5, provided in turn with a longitudinally extending reduced and an externally threaded portion 6, through which extends a central bore 7. Through said bore is adapted to reciprocate a rod 8, enlarged at its inner end 9, and threaded adjacent thereto for engagement 10 with the threads of the central bore 10 of a cylindrical member 11, having a radial flange 12 at one end, provided with a spur 13, a cylindrical section of cork or other suitable material 14 surrounding the member 11, and being pressed against the flange 12 and prevented from rotation by the spur 13 as a result of a nut 15 firmly engaging the opposite end portions of the outer threads of the member 11.

20 The rod 8 is furthermore provided at its outer end with a knob 16, by means of which the piston-head 12-14 is reciprocated within the member 1. When the interior of said last-named member, that is, the reservoir portion of the pen, is filled with a writing fluid, the parts are in the position shown in Fig. 1, and the knob 16 is covered by a ferrule 17 engaging the threads of the extension 6, said ferrule also being provided with a pencil-erasing member 18 for use as hereinafter described. When the reservoir becomes empty, and it is desired to fill the same, the rod 8 is withdrawn and then rotated until the threads upon the inner end 35 thereof engage the threads of the bore 10 of the member 11, whereupon the air is expelled from the reservoir by moving the said piston into its innermost position, thereby immersing the pen and supporting-head 3 beneath the surface of a writing fluid, and removing said piston to its outermost position as illustrated, the fluid is drawn past the pen and through the channel of the head 3 into the said reservoir.

40 The rod 8 is then rotated until its inner threaded portion is disengaged from said piston, whereupon the rod is returned to its innermost position as illustrated, and the ferrule and eraser are replaced as shown 50 in Fig. 1.

A cylindrical member 19 is provided, the same having a centrally positioned recess 20, into which the pen 4 extends (as shown in Fig. 2) when the pen portion of the instrument is not in use, and in which position the parts are retained by the threaded portion 2 of the pen engaging the threads 21 of the cylinder 19. The member 19 may be provided with a spring-clip or the like 55 22 for engagement with the pocket to prevent the instrument from accidentally becoming lost, and is also provided upon its opposite end with the reduced threaded portion 23, upon which is normally secured the 65 removable cylindrical member 24, which is

hollowed to provide a spare lead magazine 25 surrounding the tubular member 26, which is secured in spaced relation with the walls of said magazine by means of a collar 27. When the member 24 is screwed 70 upon the head 23, said tubular member surrounds a smaller tubular member 28, which at its inner end is secured to and within the said head 23, and is adapted to contain one or more leads, depending upon their 75 length, in addition to the lead 29, which is shown in Fig. 2 as in its normal position for writing.

The lead 29 is closely surrounded by the inwardly extending fingers 30, made radially yielding by longitudinally saw-cutting the otherwise outer free end portion of the tubular member 26, which portion is also externally screw-threaded to receive thereupon a tapering head 31, which when 80 screwed into the position shown in Figs. 1 and 2 engages and contracts the fingers 30 upon the outer surface of the lead 29, to prevent its accidental recession into the tube 28. The member 31 is also provided with a sharply 85 serrated portion 32, which is sufficiently abrasive to make possible the erasure of ink lines or spots by carefully manipulating it.

The bore of the tube 26 terminates outwardly in shoulders 33, forming a portion 90 of the fingers 30, which shoulders are opposed in the opposite direction by the free end portion 34 of the tube 28, but which opposed shoulders are separated to provide a reciprocation between them of a sleeve 35, 100 surrounding and in frictional engagement with the lead 29, which is exposed for use in writing purposes. Except when the tube 28 is filled, the lead 29 when not in use may be returned to an inner protected position 105 (as shown in Fig. 1) by loosening the member 31, and merely pushing the lead inwardly until the sleeve 35 abuts against the shoulder 34, whereupon the member 31 is tightened into operative position, and by 110 means of the contracted fingers 30 prevents the lead from slipping into its extended position. If the sleeve 35 engages the shoulder 34 before the lead is completely hidden by the head 32 of the member 31, while 115 the lead is loosened, the movement of the lead 29 is continued inwardly, while the sleeve slides thereupon until such inward movements ceases. Thereupon, when it is desired to expose a predetermined length of 120 lead for use, the member 31 is loosened, and the lead 29 permitted to slide therethrough by gravity, which movement will continue until the sleeve 35 co-operates with the shoulders 35, after which the member 31 is 125 tightened and the pencil portion of the instrument is ready for use.

It will then be seen that with the pen shown in Fig. 1 inverted into the inoperative position shown in Fig. 2, the pencil- 130

eraser 18 is in operative exposed position for use. When the exposed lead 29 and a second or third lead within the tube 28 have been used, and it is desired to remove additional leads from the magazine 25 into said tube 28, the member 24 is disconnected from the threaded reduced end 23 of the member 19, after which it is again screwed into position upon the transfer of leads being completed.

Having thus described my invention, what I claim and desire to protect by Letters Patent of the United States is:—

1. In a writing instrument, the combination of a pair of telescoping members, one of said members comprising a fountain pen, the other of said members comprising a magazine pencil, the pen member being provided with a pencil eraser, and the pencil member being provided with an ink eraser.

2. In a writing instrument, the combination of a pair of telescoping members, one of said members comprising a fountain pen, the other of said members comprising a magazine pencil, the pen member being provided with a pencil eraser upon the end opposed to the point and inclosed within the pencil member when the instrument is used as a pen, the pencil member being provided with an abrasive ink eraser and adapted to present no exposed lead when the pen is in use.

3. In a writing instrument, the combination of a pair of telescoping members, one of said members comprising a fountain pen, the other of said members comprising a

magazine pencil, the pen member being provided with a pencil eraser upon the end opposed to the point and inclosed within the pencil member when the instrument is used as a pen, the pencil member being provided with an abrasive ink eraser and adapted to present no exposed lead when the pen is in use, when the pencil is in use the lead being exposed and the pen member reversed, whereby the pen-point is inclosed within the pencil member and the pencil eraser is exposed.

4. In a writing instrument, the combination of a pair of telescoping members, one of said members comprising a hollow tubular fountain-pen, a piston movable longitudinally within said tube to draw ink thereinto, means for manually operating said piston extending through the end of said pen opposite to the point, and a cap supporting a pencil-eraser and normally secured upon said first member to cover said means, and the other of said members comprising a magazine pencil provided with an abrasive ink erasing surface adjacent to the pencil lead when the latter is exposed for pencil writing, said lead being adapted to slide into said pencil member when not in use, said pen member when not used for writing having its point inclosed within said pencil member and the eraser carried by said cap exposed for use in conjunction with said pencil.

In testimony whereof I have affixed my signature.

MAURICE ALLAND.
